RETRACTILE ANTENNA MAST ASSEMBLY

Gillis E. Bader, Bellville, Tex.

Application January 27, 1950, Serial No. 140,881

2 Claims. (Cl. 189—26)

1

This invention relates to retractile antenna mast assemblies and more particularly to means for supporting a mast on a derrick structure and raising and lowering the mast and is a continuation in part of my application Serial No. 93,137 filed May 13, 1949, for retractile antenna mast assembly.

It is among the objects of the present invention to provide an improved construction for pivotally connecting a tubular antenna mast to the upper end of a derrick structure for sliding, rotating and swinging movements of the mast relative to the derrick structure and to provide means associated with such improved construction for supporting the mast against bending or breaking while it is being erected on the derrick structure.

Other objects and advantages will become apparent from a consideration of the following description and the appended claims in conjunction with the accompanying drawing wherein:

Figure 1 is a side elevational view of a completely erected antenna mast assembly illustrative of the invention;

Figure 2 is a side elevation of the assembly illustrated in Figure 1 at an intermediate stage in the process of erection;

Figure 3 is a side elevation of a fragmentary portion of the antenna mast illustrating means for connecting the mast to the upper end of a mast supporting derrick structure;

Figure 4 is a cross sectional view on the line 4—4 of Figure 3; and

Figure 5 is a cross sectional view on the line 5—5 of Figure 3.

With continued reference to the drawing, the mast assembly illustrated in Figure 1 comprises, in general, a braced derrick structure 10 supported in upright position on the ground by guy wires 11, an elongated mast 12 formed of tubular sections joined together in end to end relationship, an antenna 13 supported on the upper end of the mast 12, guy wires 14 and 15 supporting the mast 12 in upright position and means 16, particularly illustrated in Figures 3, 4 and 5, connecting the mast 12 intermediate its length to the upper end of the derrick structure 10 for sliding, rotational and swinging movements of the mast relative to the derrick structure.

A fitting 17 is provided on the upper end of the mast 12 for mounting the antenna 13 and adjacent this fitting there is provided a device 18 for connecting the upper ends of the guy wires 15 to the mast. The guy wires 14 are similarly connected to the mast below the device 18 by a device 19 and the guy wires 11 are connected to the upper end of the derrick structure 10 by suitable means later to be described.

The mechanism for mounting the mast 12 on the upper end of the derrick structure 10 comprises an elongated, cylindrical sleeve 20 in which the mast is slidably and rotatably received. A flat ring or collar 21 surrounds the sleeve 20 sub-

stantially at the mid-length location of the sleeve and has a close sliding fit with the sleeve. Two internally screw threaded sockets 22 and 23 are provided on the flat ring 21 at diametrically opposite locations thereon and a bolt 24 having external screw threads at one end is threaded into the socket 22 while a similar bolt 25 is threaded into the socket 23. The bores of the sockets open through the flat ring 21 so that the bolts can be threaded into the sockets until their inner ends engage the outer surface of the sleeve 20 thereby locking the flat ring against movement relative to the sleeve.

The two side members 26 and 27 of the derrick structure 10 are provided near their upper ends with recesses or holes through which the bolts 24 and 25 extend and the bolt 24 is provided on its outer end opposite the socket 22 with a loop formation 28 to which the corresponding one of the guy wires 11 is connected while the bolt 25 is provided with a similar loop formation 29 for attachment of the remaining wire or wires of this group to the upper end of the derrick structure.

A third socket 30 is provided on the flat ring 21 midway between the two sockets 22 and 23 and projects outwardly from this ring with its longitudinal center line perpendicularly intersecting the common longitudinal center line of the ring 21 and sleeve 20. This socket 30 is provided with an internally screw threaded bore and a rod 31, preferably of tubular construction, is provided at one end with external screw threads and is threaded at such one end into the socket 30. At its opposite or outer end the rod 31 is provided with a deep, diametrically extending notch 32.

In erecting the mast assembly the derrick structure 10 is laid out flat on the ground and its bottom end pivotally connected to a suitable base structure 33 and the sleeve 20 with the flat ring 21 thereon is then placed between the upper ends of the side members 26 and 27 of the derrick structure. The bolts 24 and 25 are then inserted through the holes in the side members 26 and 27 and threaded into the sockets 22 and 23 until the sleeve is locked in the ring with the ring substantially at the mid-length location of the sleeve. The mast 12 is then inserted through the sleeve 20 beginning with the lower end of the mast and a suitable stop is provided reacting between the mast 12 and the sleeve 20 so that the mast can be used to raise the upper end of the derrick structure until the derrick structure is brought to its upright position. The mast may comprise lengths of metal tubing connected together in end to end relationship by internally screw threaded coupling collars 35 and one of these collars may be used as the stop reacting between the mast 12 and the sleeve 20 for raising the derrick structure. The guy wires 11 will have been attached to the bolt loop formations 28 and 29 before the derrick structure is raised and when the derrick structure is brought to its upright, substantially vertical position, the lower

ends of these guy wires are connected to the ground to firmly support the derrick structure in its upright position. The antenna 13 may now be mounted on the upper end of the mast 12 with the upper end of the mast positioned adjacent the ground and after the antenna is mounted, it may be raised by pulling down on the mast at a location at or near the bottom end of the latter.

In my application Serial No. 93,137, referred to above, the antenna mounted on the upper end of the mast is raised by pulling down on a ground wire connected at one end to the bottom end of the mast. As the mast is a very long structure formed of sections of light tubing, preferably aluminum tubing, secured together in end to end relationship and as the antenna 13 may be relatively heavy, it was found that this operation of raising the antenna had a tendency to bend and permanently distort the mast.

In accordance with the present invention, while the derrick structure 10 is still flat on the ground the ring 21 is mounted between the side members 26 and 27 of the derrick structure, in the manner described above, with the socket 30 extending upwardly. The rod 31 is then threaded into the socket 30 and one of the middle guy wires 15, connected at one end to the flange plate 18 by being looped through an aperture in the flange plate, as is clearly illustrated in Figure 3, is strung along the mast toward the lower end of the mast and placed in the notch 32 in the outer end of the rod 31. A staple 34 is provided on a coupling collar 35 near the bottom end of the mast 12 and the guy wire is run through this staple and looped around itself to provide a firm, tensioned transmitting connection with the staple and the portion of the guy wire below the staple is left loose.

With this arrangement, after the derrick structure 10 has been erected and guyed in upright position, the rod 31 acts as a bridge and the guy wire 15 extending from the attaching device 18 over this rod and attached to the staple 34 at the opposite side of the rod from the device 18 serves as a tension member to reinforce the mast and maintain the mast against bending or permanent distortion. The portion of the guy wire beyond the staple 34 will dangle from the mast, as illustrated in Figure 2, and may be used to pull the lower end of the mast down after the antenna has been mounted on the upper end of the mast until the mast is brought to its operative upright position. After the mast 12 has been secured in upright position the guy wire is loosened from the staple 34 and its lower end is then connected to the ground in proper position together with the other guy wires 14 and 15, to support the mast in its upright or substantially vertical operative position.

After the mast has been brought to its upright position and before the guy wires 14 and 15 are connected to the ground, the mast 12 can be adjusted both vertically and rotationally to obtain the best reception.

The invention may be embodied in other specific forms without departing from the spirit or essential characteristics thereof. The present embodiment is, therefore, to be considered in all respects as illustrative and not restrictive, the scope of the invention being indicated by the appended claims rather than by the foregoing description, and all changes which come within the meaning and range of equivalency of the claims are, therefore, intended to be embraced therein.

What is claimed is:

1. In a retractile antenna mast assembly including a derrick structure, guy wires for holding said derrick structure in upright position, an elongated mast comprising tubular sections joined together in end to end relationship, a fitting on one end of said mast for mounting an antenna thereon, guy wires for guying said mast in upright position, and means on said mast adjacent said fitting by which said last mentioned guy wires are attached to said mast, a sleeve slidably and rotatably receiving said mast, a flat ring encircling said sleeve intermediate the length of the latter, a pair of internally screw threaded sockets secured to said ring at diametrically opposite locations thereon, a bolt threaded each at one end one into each of said sockets and engaging said sleeve to fix the latter in said ring, said derrick structure having in its upper end recesses receiving the bolts, a loop formation on the other end of said bolts by which said first mentioned guy wires are attached to said bolts, a rod secured at one end to said ring between said sockets and extending perpendicularly outwardly from said ring, said rod having in its outer end a recess receiving one of said last mentioned guy wires carried from said attachment means adjacent said fitting over the outer end of said rod and attached to said mast at a location spaced from the end of said sleeve opposite said attaching means for supporting said mast against bending when the mast is swung about the common axis of said bolts.

2. In a retractile antenna mast assembly including a derrick structure, guy wires for holding said derrick structure in an upright position, a mast, means on one end of said mast for mounting an antenna thereon, guy wires for guying said mast in an upright position, means attaching said last mentioned guy wires to said mast, a sleeve slidably and rotatably receiving said mast, and a ring member encircling said sleeve, socket means formed on said ring member at diametrically opposite locations thereon, bolts affixed each at one end one in each of said socket means and engaging said sleeve to fix the latter in said ring, said derrick structure having in its upper end recesses rotatably receiving the bolts, a loop formation on the other end of each of said bolts by which said first mentioned guy wires are attached to said bolts, a rod secured at one end to said ring and extending perpendicularly outwardly therefrom, said rod having a notch formed at its outer end receiving one of said last mentioned guy wires carried from said attachment means over the outer end of said rod and attached to said mast at a location spaced from the end of said sleeve opposite said attaching means for supporting the mast against bending when the mast is swung about the common axis of said bolts.
